UNITED STATES PATENT OFFICE

JOSEPH ZAPERT, OF BROOKLYN, NEW YORK

COMBINATION KEY AND DIAL LOCK

Application filed February 19, 1929. Serial No. 341,114.

This invention relates to locks.

Its purpose is to provide a lock which can be used, for instance at night, as a combination lock, and which by changing the position of some of the parts can be used at other times as an ordinary lock, operable by means of a key.

Extending through to the outside of the door is a part of the lock casing in which is a member which can be turned by inserting a key, which is properly cut and formed, this member having on the outside a series of numbers, such as are used on dial locks.

By means of a shifting screw, the head of which projects through the back or inside of the door, the parts can be so shifted that merely by turning a key, inserted in the member at the outside of the door, the bolts can be withdrawn and the lock unlocked, or, by shifting the parts to another position, it is necessary not only to use the key to turn this member but, also, to turn it back and forth, as in a combination or dial lock.

Preferably also, I provide on the inside a knob by turning which, under certain conditions, the bolts can be thrown and the door locked or unlocked from the inside, without the use of a key, and without the use of a dial.

In the drawings, Fig. 1 is an elevation showing part of the door and casing from the outside with my lock in position with parts broken away, and the key shown in the lock. The bolts are shown in position when the door is locked.

Fig. 2 is an elevation showing part of the same door and casing from the inside, and with the door unlocked.

Fig. 3 is an elevation of the box-shaped casing, with its cover plate off and removed from the inside of the door. It is shown in the position assumed when the device is set for operation by the key and combination and when the door is unlocked.

Fig. 4 is a view similar to Fig. 3 but shows the parts in position when the door is locked so that it can only be unlocked from the outside by the use of the key and the combination.

Fig. 5 is a sectional view of the lock with

the mechanism in the position of Fig. 9 looking up in the direction of the arrows on line 7—7.

Fig. 6 is a sectional elevation as the parts would appear with the lock assembled on the door, as viewed from the right in the direction of the arrows on the line 5—5 of Fig. 1, and line 5A—5A of Fig. 4.

Fig. 7 is a view similar to Fig. 6 of the main box part of the lock, but shows the device set for operation by a key alone, the combination being drawn out of action.

Fig. 8 is an elevation similar to Fig. 4 but shows the parts set for operation by the key alone, the combination being out of action.

Fig. 9 is an elevation similar to Figs. 3, 4, and 7 showing the parts in position when the dials are turned to the position where the bolts would be withdrawn by their spring and the door would be unlocked, but showing the door locked from the inside by turning the inside knob.

Fig. 10 is a fragmentary view similar to Fig. 8 showing a slightly different construction of the device for locking from the inside by turning the inside knob.

In the drawings, A represents a door, and 1, the casing frame, which is ordinarily of wood, for the door. 2 represents the eyes, or perforated members, attached to casing 1 through which the bolts 20 of the lock pass when the door is locked.

The inside part of my lock, includes the substantially box-shaped metal casing G fastened on the inside of door A as by means of four screws 4, 4, 4, 4. 5 is a metal cover plate for casing G.

The lock really comprises two parts. One is the casing G and the parts carried in it, and the other is a cylindrical metal member, indicated generally by B, which extends through a hole 10 in door A. This includes a tubular member which as shown carries on the outside a plate 18 having a marker line 15 extending down to cylindrical opening 13 for the key barrel 12 on the outside of which are the dial numbers indicated by 14 which co-operate with marker 15 when the combination is being used with the key.

17 is the opening for the key F both of

which may be cut in any desired manner to fit each other. The inside of key barrel 12 and of the part B can be made in any well-known way whereby only the right key, such as F, can be used to engage pins 112 and turn key barrel 12.

Projecting through door A and into a slot 62 in a cam H, revoluble inside the casing G, is an extension of key barrel 12 in the form of a turning rod 162 by which the motion of the key barrel 12 and key F is transmitted to the inside lock casing G.

19, 19, 19 are hollow projections from casing G which house bolts 20, 20. These bolts are moved by the carriage 21 which connects with a coiled compression spring 22, the tendency of which is to house bolts 20, 20 in the parts 19, 19 and to keep the door unlocked.

These bolts must be positively thrown and kept housed or the door will be unlocked.

Carriage 21 is moved by means of a rocker arm M which at 23 is connected to carriage 21 by a link 27, said rocker arm being pivoted at 24 to casing G and having pivoted in a slot at its other end 25 the dog 26 located in a position, under the right conditions, to drop into the slots 76, 76, 76 in the combination discs K¹, K², K³ of a well-known type.

These discs are each provided with small screw or pin holes like 71 in which there may be positioned small flat-flister-head cap screws or pins 72 and 73 which engage each other as the discs are turned, and the outer disk K' has an outside screw head or pin 70 which is arranged to engage or not to engage with an inside pin 60, projecting from the inside of operating cam H.

This operating cam H has a boss 61 in which is the slot 62 to receive turning rod 162 and on its inside has a cylindrical hole 161 which allows it to revolve on a disc spindle 261 which projects from casing G as shown in Fig. 5.

Cam H can therefore turn on disc spindle 261 but cannot move in or out.

P in Figs. 3, 4 and 7 represents the shiftable carrier mechanism as a whole, and includes block 56 pivoted at 58, its spring 59 and a carrier plate 51, which carries the sleeve 50 slideable on disc spindle 261. Discs K¹, K², K³ are free to revolve on sleeve 50 and are separated by suitable collars.

This carrier plate 51 also carries the brake members 54, 54, 54 and their springs 55, 55, 55 of bow shape, the other ends of which are carried by the thick part 53 of plate 51 threaded to receive the shifting screw 52. Arm 57 of block 56 extends under part of plate 51 and spring 59 tends to lift both. This tendency is stopped by the action of shifting screw 52 on the thick part 53 of plate 51.

The head of this shifting screw projects from the back of casing G, and ordinarily can be covered with the sliding plate 451.

65 The keeper latch L is pivoted on block 56

at 80, and has a head 81 in which is an open slot 82 which is so positioned that when latch L is moved on its pivot, slot 82 either passes over the outside of cam 61 as shown in Figs. 3, 4, 5 and 6 or inside it so as to be engaged by pin 60 as shown in Figs. 7 and 8. Preferably a flat latch spring 85 is used to give latch L a certain amount of resiliency on its pivot 80 to avoid damage in case screw 52 is used to draw block 56 back when cam H is in the way as when the latch L and cam H are in the position in Figs. 4 and 6.

No damage can result if screw 52 is turned to release block 56 and move latch L out of engagement because the outward motion is only due to spring 59. The inward motion of block 56 is positive due to tongue 57 under the carriage 51.

The parts are so positioned that when the carrier plate 51 is moved outwardly, or towards the key F as in Fig. 6 by means of screw 52, the outside pin 70 will be engaged by the inside pin 60 on cam H. When the carrier plate is moved in the other direction however as in Figs. 7 and 8, pin 70 moves away from the path of 60, but slot 82 of latch L is moved into position so that it will be engaged by pin 60 when cam H is turned, and latch L will be so moved that its head 81 will go over underneath dog 26 as see Fig. 8, thus holding it out of slots 76, and thus locking the door by key F alone.

When operated by the key alone, cam H, as it is turned, raises the dog 26, and also moves head 81 in underneath it, thus keeping the lock locked until cam H is turned in the other direction, when pin 60 moves head 81 away from under dog 26 upon which the spring 22 unlocks the device and the door.

It will be understood that cam H can be turned only from the outside and by means of the turning rod 162 which, as shown in Figs. 1, 6 and 7 can only turn when the right key, such as F, is inserted in the barrel 12.

When the latch L is underneath or inside of cam H, as shown in Figs. 7 and 8, the combination dials K¹, K² and K³ are out of action and pin 60 inside cam H, as cam H revolves, engages the slot 82 in latch L, and moves it from the dotted line position shown in Fig. 8 at the same time that the cam itself raises the dog 26 and thus rocks arm M locking the door.

On the other hand, when it is desired to use both the key and the combination, the adjusting screw 52 is turned to move the set of dials K¹, K², K³ with the plate 51, and to allow the spring 59 to move arm 57 and block 56 together with latch L from the position shown at Fig. 7 to that shown in Fig. 6, which puts the latch L out of action but brings the dials K¹, K², K³ in such position that pins 60 and 70 will engage as the key rod 162, cam H and other parts are turned.

I also prefer to provide inside locking mechanism indicated as a whole by C.

This includes a knob 150 which is carried by a square shaft 151 which extends through 5 into the inside and carries a locking finger 159 and an unlocking finger 152. The nose or tip of finger 159 engages an arm 29 on rocker M when knob 150 is turned and brings the parts from the position shown in Fig. 3 10 to that shown in Fig. 9.

As the point of contact between finger 152 and finger 159 bears such relation to the pivots 24 and 151 as to be almost on dead center, the keeper 26 is held substantially out of 15 action and the door is locked.

The door can be unlocked by turning knob 150 from the inside or by turning cam H by key F from the outside of the door when pin 60 engages finger 152 lifting it and thus 20 finger 159, thereby releasing catch 156 so that spring 153 acting on the sides of the tail on finger 152 turns it to position of Fig. 3, and allows the spring 22 to unlock the door.

This spring 153 is held between the pins 25 154 and 155 and is bent at 156 to form a catch to engage a small projection on the hub which carries the fingers 152 and 159 as shown in Fig. 9. The spring can be dispensed with, if desired, as shown in Fig. 10.

30 As shown in Fig. 10, by changing the shape of arm 29 as shown at 429 and by changing the shape of finger 159 as shown at 459 so that the latter presents a flat surface at 458 to arm 429, the force tending to move arm 429 35 in the direction of the arrow acts on a dead center towards pivot 151 and the parts are held in that position with no spring and with no brake.

Other means may be used to lock the door 40 from the inside by holding the bolts, or such means may be omitted altogether.

For convenience in some of the claims, I will call the front that side of the lock from which the barrel projects, and the side where 45 the knob 150 projects, the back.

I claim:

1. The combination in a lock casing which 50 houses a bolt and a returning spring therefor; of a pivoted rocker arm one end connecting with the bolt and the other end having a dog in operative relation with a series of slotted discs; said series of slotted discs revolvable on shiftable carrier mechanism, the outside disc having a contact pin; said shiftable carrier mechanism for said 55 series of slotted discs and for a dog; said dog pivoted to the shiftable carrier mechanism and having a slotted jaw spaced outside of said outside disc; means operative from the back of the casing to move the shiftable carrier mechanism, dog and series of discs axially; a revolvable operating cam having a turning slot and so positioned as to engage 60 the dog and having an inside pin in position to engage said outside contact pin or the jaw 65

of the dog according to the position of the shiftable carrier mechanism; and a barrel at the front which is marked with dial numbers, said barrel being turnable only by a key which fits pins inside the casing, and having a turning rod fixed to the barrel and which enters the turning slot in said cam; together with a knob turnable from the back of the lock casing carried by a spindle which extends inside the casing and has a finger so positioned as to move the rocker arm into a substantially dead center position and thereby hold the bolt against the returning spring.

2. The combination in a lock having a bolt and a returning spring therefor; of a pivoted rocker arm one end connecting with the bolt and the other end having a dog in operative relation with a series of slotted discs; said series of slotted discs revolvable on shiftable carrier mechanism, the outside disc having a contact pin; said shiftable carrier mechanism for said series of slotted discs and for a dog; said dog latch pivoted to the shiftable carrier mechanism and having a slotted jaw spaced outside of said outside disc; means to move the shiftable carrier mechanism, dog and series of discs axially; a revolvable operating cam so positioned as to engage the dog 80 and having an inside pin in position to engage said outside contact pin or the jaw of the dog according to the position of the shiftable carrier mechanism; and a barrel positioned at the front of the lock and connected to the cam, such barrel having an outside numbered dial and being turnable only by the right key; together with means from the back side of the lock to hold the bolts in 85 locking position.

3. The combination in a lock having a bolt and a returning spring therefor; of a pivoted rocker arm one end connecting with the bolt and the other end having a dog in operative relation with a series of slotted discs; said series of slotted discs revolvable on shiftable carrier mechanism, the outside disc having a contact pin; said shiftable carrier mechanism for said series of slotted discs and for a dog; said dog pivoted to the shiftable carrier mechanism and having a slotted jaw spaced outside of said outside disc; means to move the shiftable carrier mechanism, dog and series of discs axially; a revolvable operating cam so positioned as to engage the dog and having an inside pin in position to engage 90 said outside contact pin or the jaw of the dog according to the position of the shiftable carrier mechanism; and a barrel connected to the cam, such barrel having an outside numbered dial and being turnable only by the right key; together with means from the back side of the lock to hold the bolts in 95 locking position.

4. The combination in a lock having a bolt and a returning spring therefor; of a pivoted rocker arm one end connecting with the bolt and the other end having a dog in operative relation with a series of slotted discs; said series of slotted discs revolvable on shiftable carrier mechanism, the outside disc having a contact pin; said shiftable carrier mechanism for said series of slotted discs and for a dog; said dog pivoted to the shiftable carrier mechanism and having a slotted jaw spaced outside of said outside disc; means to move the shiftable carrier mechanism, dog and series of discs axially; a revolvable operating cam so positioned as to engage the dog and having an inside pin in position to engage 100 said outside contact pin or the jaw of the dog according to the position of the shiftable carrier mechanism; and a barrel connected to the cam, such barrel having an outside numbered dial and being turnable only by the right key; together with means from the back side of the lock to hold the bolts in 105 locking position.

5. The combination in a lock having a bolt connected to a dog which is movable with the bolt; of a barrel at the front of the casing having a numbered dial and being turnable 110
